A. L. OLSON

CLOSURE FOR JARS, CANS, AND THE LIKE

Filed April 23, 1924

Inventor
Anton Lawrence Olson

By Bradbury & Caswell
Attorneys

UNITED STATES PATENT OFFICE.

ANTON LAWRENCE OLSON, OF WELCH, MINNESOTA.

CLOSURE FOR JARS, CANS, AND THE LIKE.

Application filed April 23, 1924. Serial No. 708,422.

My invention relates to improvements in closures for jars, cans and the like.

An object of the invention is to provide a simple and inexpensive closure adapted to be readily applied to and removed from the neck of a container, and when so applied to hermetically seal the container.

Another object is to provide a closure of the instant nature constructed to effect a serviceable sealing grip upon the neck of a container and designed to open the container to the outer atmosphere in a seal breaking operation performed, in releasing the grip of the closure upon the container neck, preparatory to the withdrawal of the closure from the neck.

With the foregoing and other objects in view, which will appear in the following description, the invention resides in the novel combination and arrangement of parts and in the details of construction hereinafter described and claimed.

In the drawing, Fig. 1 is a longitudinal, central, sectional view of a closure embodying my invention, the same being shown as capping the threaded neck of a jar; Fig. 2 is a view similar to Fig. 1, except that the stopper member of the closure is shown as being compressed in jar sealing relation; Fig. 3 is a transverse, sectional view taken as on the line 3—3 of Fig. 1 and Fig. 4 is a view of a closure illustrated as applied to the neck of a can, said closure being partly broken away to show the encased resilient stopper in close conformity with the contour of the threaded neck of the can.

In the drawing, wherein similar reference characters are used throughout the several views to indicate like parts, it will be observed that my improved closure includes a stopper *a*, a sleeve 10 closely encircling said stopper, a clamping plate 11 within the sleeve 10, a cover *b* for the sleeve and a combined bearing and valve element *c* interposed between the cover *b* and plate 11.

The stopper *a*, formed of live rubber or other suitable resilient material, comprises a crown-piece 12 having an annular flange 13 depending therefrom, said stopper providing a cap adapted to snugly fit the neck 14 of a container 15. The crown-piece 12 is formed with a small aperture 16 reaching axially therethrough and serving a purpose soon to be explained.

The sleeve 10 constitutes a cage for the stopper *a*, said sleeve being formed with an

inturned flange 17 at the bottom thereof to supply an abutment for the flange 13 of said stopper *a*.

The clamping plate 11 as herein disclosed, 60 consists of an arched disc, which is slidably guided longitudinally of the sleeve 10 and adapted to cover and bear down upon the crown-piece 12 of the stopper *a*. Concentric beads 18 are formed on the under side of the 65 clamping plate 11 and a central bore or opening 19 is made in said plate, the same being beveled, as shown.

The cover *b* includes a top 20 and a flange 21 depending therefrom. The flange 21 70 robustly telescopes the upper end of the sleeve 10 and the top 20 is axially depressed to better resist upward pressure thereagainst. A pin 22, secured at its ends in said flange 21, reaches through diametrically opposed cam 75 slots 23 formed in the upper margin of the sleeve 10.

The combined bearing and valve element or spindle *c* depends from the center of the top 20 of the cover *b* to which it is secured. 80 The pin 22 passes through this spindle *c* medially thereof. The lower end of said spindle *c* is beveled to conform with the angle of the seat formed by the beveled opening 19 in the plate 11, the point 24 formed 85 by thus beveling said spindle being sufficiently long to reach through said opening 19 and plug the aperture 16 in the crown-piece 12 of the stopper *a*.

In applying the closure to a container, 90 the stopper *a* is slipped over the neck of the container (Fig. 1). The sleeve 10 is then held against rotation and the cover *b* turned to the right. By thus turning said cover 95 it is brought downward on the sleeve 10 through the coaction of the pin 22 with the cam slots 23 in said sleeve 10. This movement of the cover *b* on the sleeve 10 carries the spindle *c* into engagement with its seat in the clamping plate 11 and said plate 11, 100 in turn, is forced against the stopper *a* (Fig. 2). Resting upon the abutment 17 on the sleeve 10 and confined against outward distortion by said sleeve, the flange 13 of the stopper *a* is compressed and conforms with 105 that portion of the neck 14 embraced thereby. Thus distorted, under pressure of the clamping plate 11, the flange 13 of the stopper *a* firmly grips the container neck 14 and supplies an effective seal therefor. Said 110 clamping plate 11, due to its arched form, crowds the stock of the crown-piece 12 ax-

ially thereof and thus closes the aperture 16 therein, the sealing effect of said aperture, in closing, being augmented by the simultaneous plugging thereof by the tip of the point 24 on the spindle *c*. The concentric beads 18 on the under side of the compression plate 11 seat themselves in the crown-piece 12 of the stopper *a* and further insure the sealing of the container. The pin 22 passing through the spindle *c* braces the cover top 20 against distortion under the strain of depressing the clamping plate 11. The cam slots 23 are arranged to correspond with the usual right hand threads of a container neck, so that the final stage in the turning of the cover *b* to complete the sealing operation can be effected without holding the sleeve 10 and with the result of bringing the crown-piece 12 tightly against the rim of the container neck 14. This effect will be readily understood when it is remembered that the inner wall of the flange 18 is forced into conformity with the threads of the container neck during the initial stage of the turning of the cover *b*, when the user holds the sleeve 10 against rotation. Each cam slot 23 has a short, lateral reach 23^a at the lower extremity thereof and the ends of the pin 22 resting in these reaches in the sealing relation of the cover *b* are secure against accidental seal breaking displacement.

In removing the closure from a container, the cover *b* is turned to the left to bring the ends of the pin 22 to the upper extremities of the cam slots 23. In thus loosening said cover, the compressing action of the plate 11 is discontinued and the spindle *c* withdrawn from position closing the opening 19 in said plate and plugging the aperture 16 in the crown-piece 12 of the stopper *a*. With the pressure of the clamping plate 11 removed, the stopper *a*, will assume its original form (Fig. 1), the opening of the aperture 16 permitting of the equalization of pressures within and without the container, after which the closure may be safely and easily lifted from the neck of the container. Should the neck be threaded and the flange 18 of the stopper cling to the threads, a simple unscrewing motion of the entire closure will easily effect the removal of the same from the container.

Among the several advantageous features resident in my improved closure are simplicity and low cost of construction. The ease of application and removal of the closure coupled with the effectiveness of the seal produced by the closure are also important features.

Changes in the specific form of my invention, as herein disclosed, may be made within the scope of what is claimed without departing from the spirit of my invention.

Having described my invention, what I

claim as new and desire to protect by Letters Patent is:

1. A unitary device of the class described comprising a resilient stopper including a crown-piece and a depending annular flange integral therewith, said stopper being adapted to receive the neck of an ordinary container, said crown-piece having an axial aperture therein, a sleeve closely encasing said stopper and formed with cam slots in the upper margin thereof, an inverted flange at the bottom of the sleeve forming an abutment for the flange of the stopper, a clamping disc slidably guided within said sleeve and superimposing the stopper, said disc having an axial opening therein, a cover revoluble on said sleeve and dished inward at the top thereof, a bearing depending axially from the inwardly dished top of said cover, the lower end of said bearing being tapered to a point axially thereof and adapted to the seat in the axial opening in said clamping disc, a pin reaching through said bearing and said cam slots in said sleeve and anchored at its ends in the flange of the cover, said pin serving to relieve the top of the cover against strains and also cooperating with the cam slots in said sleeve to depress the cover, whereby said bearing is caused to seal the opening in the clamping disc, plug the aperture in said stopper and forcibly bring said disc against the stopper, the co-operation of said pin with said cam slots serving further to elevate the cover, whereby the bearing is lifted from position wherein said opening and aperture are sealed thereby and the disc forced against said stopper.

2. In an article of the class described, a resilient stopper adapted to cap the neck of a container, a sleeve closely encircling the stopper, and formed with cam slots therein, a rest on the sleeve for the bottom of the stopper, a stopper clamping plate within the sleeve above said stopper, a cover for the sleeve having a depending flange over-reaching the cam slots in said sleeve, a bearing depending from the cover axially thereof and adapted to bear against said plate and a pin secured at its ends in the flange of the cover, said pin reaching through said cam slots and also through said bearing.

3. In an article of the class described, a resilient stopper adapted to receive the neck of an ordinary container, a sleeve closely encircling said stopper, an abutment at the lower end of the sleeve for the bottom of the stopper, a clamping member guided within said sleeve and superimposing said stopper, a cover on the upper end of the sleeve, a bearing depending axially from the cover and co-operating cam devices associated with said cover and sleeve, said cam devices serving, upon the rotation of said cover in one direction on said sleeve, to bring said bear-

ing against the clamping member and said member, in turn, against the stopper, whereby the latter is compressed and thereby caused to grip the container neck.

5 4. In a unitary article of the class described, a resilient member adapted to closely cap the neck of a container, the crown of said cap member being formed with a venting aperture therein, a cage for said member, a compression plate formed with an opening therein and arranged within the cage above said member, a combined bearing and valve element adapted to bear against said plate and close said opening and means 10 carried by the cage for operating said element to compress said resilient member, whereby the annular flange thereof is spread radially into neck gripping and sealing form and the crown of said member compressed 15 to close said aperture.

20 5. In a unitary article of the class described, a resilient member adapted to closely cap the neck of a container, the crown of said cap member being formed with a venting aperture therein, a cage for said member, a compression plate within the cage superimposing said member, and means on the cage for forcing the plate against said member, whereby the annular flange thereof is spread radially into neck gripping and sealing form and the crown of said member compressed to close said venting aperture.

25 6. In a device of the class described, a resilient stopper adapted to cap the neck of an ordinary container, a sleeve containing said stopper, an abutment on said sleeve for the bottom of the stopper, a stopper compressing member within the sleeve and means on the sleeve to force said member against the stopper and thereby radially spread the same into neck gripping and sealing form.

30 7. In an article of the class described, a resilient stopper adapted to cover the neck of a container, said stopper having an air admitting aperture therethrough, a cage for

the stopper, a plate within the cage for compressing the stopper therein and means for bringing said plate to bear upon the stopper, said plate presenting a concave surface to the stopper and adapted, upon pressing 50 against said stopper, to distort the same radially and close said aperture therein.

8. An article of the class described comprising a resilient annular member, a sleeve-like cage closely encircling the same, an abutment for one end of the annular member and a second abutment movable toward and from the first abutment for the other end of the resilient annular member, said member, cage and abutments constituting parts of a unitary structure bodily applicable to and removable from the neck of an ordinary container, said resilient member, in the normal form thereof, being adapted freely to receive the container neck, and means constituting 60 an additional part of said unitary structure for moving one abutment with respect to the other to compress the resilient member axially thereof and thereby spread said member 65 radially inward, within its peripherally confining cage, into neck gripping form.

25 9. An article of the class described comprising a resilient member, an abutment for one end thereof and a second and relatively movable abutment for the other end thereof, 70 said member and abutments constituting parts of a unitary structure bodily applicable to and removable from the neck of an ordinary container, said resilient member being adapted, in its normal form, to be readily applied to the container neck preparatory to sealing the same, and means constituting an additional part of said unitary structure for moving one abutment with respect to the other to compress the resilient member axially 75 thereof and thereby spread said member 80 radially into neck gripping form.

In testimony whereof, I have signed my name to this specification.

ANTON LAWRENCE OLSON.
